BURNER ASSEMBLY

Bennett J. Moore, Detroit, Mich., assignor to Magic Servant Products Company, Detroit, Mich., a corporation of Michigan

Filed Aug. 21, 1964, Ser. No. 391,140
20 Claims. (Cl. 239—399)

This invention relates to heating units and more particularly has reference to an improved burner construction for such a unit.

In many conventional burner assemblies, air supplied from the blower unit is split into primary and secondary airstreams. The primary air is mixed with the gas and directed to the pilot unit for combustion within the combustion chamber. The secondary air is directed to the combustion chamber where it mixes with the unburned gas in the primary airstream producing complete combustion of the gas, and causes the heated air to rise in the combustion chamber.

An important problem associated with this type of burner is that of adjusting the amount of air provided respectively in the primary and secondary airstreams. When the burner is installed or adjusted the air intake at the blower unit is usually adjusted to vary the volume of air delivered to the combustion chamber. In addition, the volume of air provided respectively in the primary and secondary airstreams is also manually varied in order to produce complete combustion of the gas and the proper movement of the heated air within the combustion chamber. In other words, adjustment of the burner normally requires that the air flow be adjusted both at the blower intake and at the entrance to the combustion chamber. This dual air adjustment considerably complicates installation or adjustment of the burner assembly.

As will be subsequently described in detail, in a preferred embodiment of the present invention a burner assembly is provided having an air splitter member integral with the mounting plate fastening the burner to the wall of the hearth or combustion chamber. The air splitter is adapted to provide a pre-set ratio of primary to secondary air flow regardless of the volume of air supplied from the blower. As a result, adjustment of the burner assembly requires adjustment of the air flow only at the intake of the blower unit.

The present invention is particularly suited as a conversion burner for existing oil burners. A major problem associated with converting such oil burners is that of providing the same amount of heat as was provided with the oil burner in the existing combustion chamber space. Gas burners normally require more space than oil burners to produce the same quantity of heat and consequently conversion units heretofore in use have been inefficient, expensive and hence inadequate for most installations. In addition, these conversion units are frequently characterized by unpleasant noise and pulsations.

The present invention provides means for spinning the primary gas-air mixture and "upshot" firing of this mixture in the hearth while the secondary air is directly fired or "inshot" into the chamber. As a result, noise and pulsation are substantially eliminated and the burner is capable of operating in a combustion chamber of smaller size than that required for conventional gas burners. I have found that my gas burner requires a combustion chamber with only 25% of the volume presently required for available gas burners. My burner will develop the same amount of heat as the replaced oil burner, in the same combustion chamber, and without noise or pulsation.

The one-piece splitter and mounting plate permits the entire burner to be of a far more compact and simple construction than is possible with conventional burners.

2

In addition, while most burners employ a Venturi or similar structure within the conduit carrying the primary air and gas, I employ a baffle within the conduit adjacent the gas inlet which provides turbulence in the air-gas flow stream and permits the conduit to be of considerably shorter length than that required when a Venturi is employed. This feature, along with those mentioned above, permits the burner to operate within a hearth of considerably smaller size than that required for conventional burners of the same capacity.

It is accordingly an object of the present invention to provide a burner assembly of simple and compact design adaptable for use with furnaces having relatively small combustion chambers.

Another object of the present invention is to provide a conversion gas burner assembly adapted to operate in the same combustion chamber as the original oil burner, at the same capacity, and without noise or pulsation.

Another object of the present invention is to provide a burner assembly in which a pre-set ratio of primary to secondary air is provided regardless of the volume of air delivered by the blower.

Still another object is to provide a burner assembly of this kind which is of simple construction and of low manufacturing cost.

Other objects and advantages of the present invention as well as various other novel features of the invention will be more readily apparent from the following detailed description of a preferred embodiment thereof. The description makes reference to the drawings in which:

FIG. 1 is an end elevational view of a burner assembly according to a preferred embodiment of the present invention;

FIG. 2 is a side elevational view of the burner assembly of FIG. 1;

FIG. 3 is a cross-sectional view taken along the lines 3—3 of FIG. 2;

FIG. 4 is a cross-sectional view taken along the lines 4—4 in FIG. 2;

FIG. 5 is a detail plan view taken along the lines 5—5 in FIG. 2; and

FIG. 6 is a cross-sectional view taken along the lines 6—6 in FIG. 5.

Description

Referring to the drawings in detail, the present burner assembly is shown adapted for mounting on the hearth or combustion chamber wall 13 of a conventional furnace as shown in FIG. 2. The burner assembly includes a disc-shaped splitter member 10 having a peripherally extending mounting flange 11 adapted to be mounted to the wall 13 and a pair of parallel axially extending bosses 12 and 14 projecting from one side as can best be seen in FIG. 4. The boss 12 surrounds a circular air inlet 16 while the boss 14 surrounds a smaller circular gas inlet 18. A third boss 20 is provided on the opposite side of the splitter member 10 as shown in FIG. 4 which is substantially coextensive with the gas inlet 18 and with a portion of the air inlet 16. A gas conduit 22 fits within the boss 14 while a blower exhaust tube 24 is secured in the larger boss 12 by means of tightening screw 26. A mixing or upshot tube 28 projects into the combustion chamber indicated generally at 15 in FIG. 2 interiorly of the wall 13 and is secured in place in the boss 20 on the opposite side of the splitter member 10. The tube 28 includes a small baffle 30 which projects into the interior of the tube immediately across from the gas inlet 18. A baffle 31 is secured to the mounting flange 11 by means of screws 33 and is disposed across a portion of the inlet 16. Thus gas introduced through the conduit 22 is directed into the interior of tube 28 and strikes the baffle 30. Air delivered from the blower, which will be described in detail below,

moves along the exhaust tube 24 and is split or divided into primary and secondary air streams so that a portion of the air (primary air flow) moves into the tube 28 and a portion (the secondary air stream) is inshot or passed through the splitter member 10 outside of the tube 28 and is deflected or agitated by the baffle 31. The air and gas entering the mixing tube 28 are thoroughly mixed due to the turbulence created by the baffle 30 across the flow stream.

As can best be seen in FIGS. 1 and 2, the blower assembly 32 comprises a motor unit 34 adapted to drive a conventional blower unit 36. The air intake for the blower unit 36 is provided with a threaded bolt 38 on which a disc-shaped seat 40 is adapted to move axially. A nut 42 threadably engages the bolt 38 and limits the outward movement of the seat 40 along the bolt. The seat 40 limits the volume of air pulled into the interior of the blower unit 36; thus, by adjusting the position of the nut 42 and the seat 40 the volume of air pulled into the blower unit 36 and hence delivered for combustion, may be controlled. The blower unit 36 delivers air into the exhaust tube 24 where it is split, as described above, the primary air moving into the mixing tube 28 and the secondary air passing into the interior of the combustion chamber (not shown) externally of the mixing tube 28.

Gas is delivered to the burner through a gas intake tube 44 which is connected through elbow 46 to a conventional valve member 48. The latter member is adapted to direct a portion of the gas delivered from the gas delivery tube 44 through a gas line 50 and an L-shaped valve member 52 to a T-shaped connector 56. The connector 56 directs a portion of the gas along a line 58 to another valve 60 which delivers the gas to a conventional perforated lighter tube 64 which extends through an opening in the splitter member 10. The outer end of the lighter tube 64 is supported on an L-shaped bracket member 66 which is rigidly secured to the upwardly turned end of the mixing tube 28.

The connector 56 also directs gas through a line 68 to a central valve control 70 which in turn directs the gas through a line 72 which extends to a point opposite the face of the splitter member 10. The tube 72 is connected, through a suitable mechanical connection, to a nut 74 which is fixed within a hole in the splitter member 10. The opposite side of the nut 74 is connected to a pilot tube 76 which terminates at its outer end in a pilot assembly 78 of the conventional variety supported on the bracket 66 adjacent the lighter tube 64.

A thermocouple 80 extends from the central valve member 70 through a hole in the splitter member 10 to a point adjacent the orifice of the pilot assembly 78 and is supported in place on the bracket 66.

The central gas tube 44 is connected through a conventional pressure regulator 82 and an elbow 84 to the interior of the central valve control 70. The valve control 70 is actuated through an electrical control unit 86 connected to a suitable source of electrical power (not shown). The electrical control unit 86 is connected to the central valve member 70 through the cable indicated at 88 and into the blower assembly 32 by suitable means (not shown).

A deflector or spinner 90 is provided at the upper outer end of the mixing tube 28. As shown in FIGS. 5 and 6, the deflector or spinner 90 is fluted, having a number of spaced inclined vanes or flutes 92 extending radially outward from a central hub 94. The deflector 90 is cup-shaped in cross section as can best be seen in FIG. 6 with the vanes 92 disposed in concave fashion within the end of the mixing tube 28. The vanes 92 are separated by radially extending strips 96 extending outwardly from the hub 94, each vane 92 being bent to form an angle with the plane of the strips 96 and to provide radially and circumferentially extending openings 98 therebetween. These openings 98 spin the air-gas mixture as it issues

through the tube 28. The concave shape of the spinner 90 causes this issuing gas-air mixture to be concentrated at a point directly above the deflector 90, for ignition by the pilot assembly 78. The spinner 90 is removable from the end of the mixing tube 28 and, if desired, may be inverted so as to be convex upward. In such a case, the spinner 90 will act to spread the air-gas mixture outwardly as it issues from the mixing tube 28.

When installing the present burner assembly either as a conversion unit or in a new heating system, the splitter 10 is fastened across a suitable opening 17 in the wall 13 of the combustion chamber 15, as shown in FIG. 2. The configuration of the mounting flange 11 on the splitter member 10 will depend upon the size and shape of the opening 17 in the combustion chamber wall 13. In the splitter member shown in the drawings, the mounting flange 11 is circular with regularly spaced recesses 100 which are adapted to receive suitable bolts for securing the splitter member 10 to the wall 13 of the combustion chamber 15. However, the shape of flange 11 will vary depending upon the hearth upon which it is to be mounted. When the splitter member is thus mounted in place, the mixing tube 28, the lighter units 64, and the pilot assembly 78, all project into the interior of the combustion chamber 15.

In operation, the present burner assembly is started in the conventional fashion, by permitting gas to flow through gas line 58 to the lighter assembly 64 and lighting the lighter assembly 64 so that a flame is produced at its outer end adjacent the end of the mixing tube 28. This flame heats the thermocouple 80 which in turn causes the central valve control 70 to direct gas into the pilot gas line 72 and thence into the pilot assembly 78. The issuing gas at the end of the pilot assembly 78 is ignited by the lighter assembly 64.

The air intake at the blower assembly 32 is adjusted by suitably positioning the nut 42 and the seat 40. With each actuation from the electrical control unit 86, the blower motor 34 causes air to be pulled into the blower unit 36 and forced through the blower exhaust portion 24 to the splitter member 10 where the air is split into the primary and secondary air streams. Gas supplied from the gas line 44 through the pressure regulator 82 and the central valve control 70 is introduced into the gas inlet tube 22 where it is directed against the baffle 30 disposed along the interior of the mixing tube 28. The baffle 30 causes the gas and primary air entering the mixing tube 28 to be agitated and thereby thoroughly mixed. The air-gas mixture issuing at the upper end of the mixing tube 28 is ignited by the pilot assembly 78. The baffle 31 on the combustion chamber side of the splitter member 10 causes the secondary air diverted into the combustion chamber to flow around the mixing tube and thereby thoroughly fill the combustion chamber. This secondary air aids in the complete combustion of the gas issuing from the mixing tube 28, and causes the heated air to rise in the combustion chamber.

The mixing tube 28 is preferably, as shown in the drawings, of the upshot variety; however, in certain situations the tube may be straight with the combustion occurring at one horizontal end. I have found that by employing a splitter member of the type shown, together with the baffles 30 and 31 a shorter mixing tube 28 may be employed than is commonly used with burner assemblies of the present type. This enables the present burner assembly to be used as a conversion unit for existing furnaces having relatively small combustion chambers. I have found that the present burner can operate in a hearth of one-fourth the size of that conventionally required for the same capacity burner. In addition, the present burner operates in the same combustion chamber as the original oil burner, at the same capacity, and without noise or pulsation.

With the present burner assembly a pre-set ratio of primary to secondary air is obtained regardless of the vol-

ume of air delivered by the blower assembly 32. As a result, each time the volume of air delivered from the blower assembly is varied, adjustment of the proportion of air in the primary and secondary air streams is not necessary. This assures complete combustion within the furnace regardless of the efficiency or setting of the the blower assembly.

It will be apparent to those skilled in the art to which this invention pertains that various changes and modifications may be made without departing from the spirit of the invention or the scope of the appended claims.

I claim:

1. A burner assembly, comprising
  - (a) an air blower assembly,
  - (b) a gas delivery line,
  - (c) a mixing tube disposed within the combustion chamber of a furnace,
  - (d) a splitter member mounted within an opening in the wall of said combustion chamber to receive said air and gas respectively from said blower assembly and gas line externally of said combustion chamber, said splitter member delivering said gas and a preset proportion of said air to said mixing tube regardless of the volume of air delivered from said blower assembly, the remainder of said air being delivered to said combustion chamber externally of said mixing tube.
2. The burner assembly as set forth in claim 1 and including a baffle mounted within said mixing tube adjacent said splitter member and adapted to produce turbulence in said mixing tube, said turbulence producing mixing of said gas and the air delivered to said mixing tube.
3. The burner assembly as set forth in claim 1 and including a baffle member in said combustion chamber adjacent said splitter member and disposed externally of said mixing tube and adapted to deflect the air delivered to said combustion chamber externally of said mixing tube.
4. The burner assembly as set forth in claim 1 and wherein said blower assembly includes an air inlet, a threaded shaft extending through said inlet, a seat adapted to move along said shaft, the position of said seat determining the volume of air drawn through said inlet, and a nut member threadably engaging said shaft and adapted to limit the movement of said seat along said shaft and thereby limit the volume of air drawn through said air inlet.
5. The burner assembly as set forth in claim 1 and including a deflector member at the combustion end of said mixing tube, said deflector having a plurality of deflecting vanes arranged in cup-shaped fashion across said end of said mixing tube.
6. The burner assembly as set forth in claim 5 and wherein said deflector member is removably mountable in said mixing tube in one of two positions, the first of said positions having said vanes extending in concave fashion across the said end of said mixing tube, and the second of said positions having said vanes extending in convex position across said end.
7. A burner assembly, comprising:
  - (a) an air blower assembly,
  - (b) a gas delivery line,
  - (c) a mixing tube disposed within the combustion chamber of a furnace,
  - (d) a splitter member comprising a mounting flange securing said burner assembly to the wall of said combustion chamber, a gas inlet receiving gas from a gas delivery line, an air inlet receiving air from said blower assembly, said splitter member delivering said gas and a preset proportion of said air to said mixing tube regardless of the volume of air delivered from said blower assembly, the remainder of said air being delivered to the interior of said combustion chamber externally of said mixing tube.
8. The burner assembly as set forth in claim 7 and including a baffle mounted in said mixing tube opposite

said gas inlet and adapted to produce turbulence in the gas flowing from said inlet into said mixing tube, and to thereby mix said gas and said air delivered to said mixing tube.

9. The burner assembly as set forth in claim 7 and including a baffle in said combustion chamber opposite said air inlet and disposed exteriorly of said mixing tube, said baffle deflecting the air entering said combustion chamber externally of said mixing tube.

10. The burner assembly as set forth in claim 7 and wherein said blower assembly includes an air inlet, a threaded shaft disposed within said inlet, a seat adapted to move along said shaft, the position of said seat determining the volume of air drawn through said inlet, and a nut threadably engaging said shaft and limiting motion of said seat in the direction away from said inlet, said nut thereby controlling the volume of air entering said blower assembly.

11. The burner assembly as set forth in claim 7 and including a deflector mounted at the combustion end of said mixing tube, said deflector comprising a plurality of radially extending deflector vanes disposed in cup-shaped fashion across said end of said mixing tube.

12. The burner assembly as set forth in claim 11 and wherein said deflector is removably mounted in said mixing tube in one of two positions, in the first of said positions said vanes being disposed in concave fashion with respect to said end of said mixing tube, in the second of said positions said vanes extending in convex manner across said ends of said mixing tube.

13. The burner assembly, comprising:

- (a) an air blower assembly,
- (b) a gas delivery line,
- (c) an upshot mixing tube disposed within the combustion chamber of a furnace,
- (d) a splitter member comprising a mounting flange securing said splitter member within an opening in the wall of said combustion chamber, a gas inlet receiving gas from said delivery line, an air inlet receiving air from said blower assembly, an outlet on the side of said splitter member opposite to said gas inlet and air inlet, said outlet delivering said gas and a preset proportion of primary air from said air inlet to said upshot mixing tube regardless of the volume of air delivered from said blower assembly, said outlet delivering the secondary air to the interior of said combustion chamber externally of said mixing tube.

14. The burner assembly as set forth in claim 13 and wherein said gas and air inlets comprise axially extending openings on the side of said splitter member away from said combustion chamber, and said outlet comprises a circular opening on the side of said splitter member facing said combustion chamber, said outlet being co-extensive with at least a portion of said gas inlet and said air inlet.

15. The burner assembly as set forth in claim 13 and including a baffle in said mixing tube at said outlet and adapted to produce turbulence in the gas entering said outlet from said gas inlet.

16. The burner assembly as set forth in claim 13 and including a baffle in said combustion chamber disposed externally of said mixing tube and adapted to deflect said secondary air as it enters said outlet.

17. The burner assembly as set forth in claim 13 and wherein said blower assembly includes an air inlet, a threaded shaft extending adjacent said inlet, a seat co-extensive with said inlet and movable along said shaft, and a nut threadably engaging said shaft and adapted to limit the motion of said seat so as to limit the volume of air delivered through said air inlet to said blower assembly.

18. The burner assembly as set forth in claim 13 and including a spinner at the combustion end of said mixing

tube, said spinner comprising a plurality of deflecting vanes arranged in cup-shaped fashion across said end of mixing tube.

19. The burner assembly as set forth in claim 13 and including a spinner at the combustion end of said mixing tube, said spinner comprising a plurality of deflecting vanes arranged in cup-shaped fashion across said end of said mixing tube.

20. The burner assembly as set forth in claim 18 and

wherein said spinner is removably mountable in one of two positions in the first of said positions said vanes extending in concave fashion across said end of said mixing tube, and in the second of said positions said vanes extending in convex fashion.
